CHARLES PAFF, OF NEW YORK, N. Y.

RETAINING-WALL FOR EMBANKMENTS.

1,349,166.

Specification of Letters Patent. Patented Aug. 10, 1920.

Application filed May 25, 1918. Serial No. 236,484.

To all whom it may concern:

Be it known that I, CHARLES PAFF, a citizen of the United States, and a resident of New York, in the county of New York and 5 State of New York, have invented a certain new and useful Improvement in Retaining-Walls for Embankments, of which the following is a full, clear, and exact specification.

This invention relates to a class of walls, 10 or abutments adapted for use in conjunction with embankments.

My invention has for its object primarily to provide a form of wall designed to be constructed for retaining the edge of an embankment of earth, gravel and the like when required to accomplish certain classes of construction work, and which is especially adaptable of being built of cement, in order to save the expense, time and labor incident 20 to constructing such walls of stone. The invention consists essentially of providing a series of pockets with orificed walls on one face of an upwardly disposed wall member with a base adapted to be embedded at the 25 edge of an embankment of earth, gravel and the like so that the wall will be anchored in the edge part of the embankment by its material being received in the pockets as well as in the orifices of the walls of the pockets.

30 A further object of the invention is to provide a retaining wall adapted to be constructed so as to combine great strength and durability, and which is susceptible of being made in any suitable length and height.

35 A practical embodiment of the invention is represented in the accompanying drawing which forms a part of this specification in which similar characters of reference indicate corresponding parts in all the views, the said invention being more fully described hereinafter and then pointed out in the 40 claims at the end of the description.

In the drawing, Figure 1 is a fragmentary view, partly broken away, showing a detail 45 section of one form of retaining wall embodying my invention taken on the line I—I of Fig. 2 as well as showing the manner of its use for holding the edge of an embankment.

Fig. 2 is a fragmentary view, partly 50 broken away, showing a front elevation of the wall.

Fig. 3 is a fragmentary view, partly 55 broken away, showing a rear elevation of the wall, and

Fig. 4 is a fragmentary view, partly

broken away, showing a perspective of part of my improved wall.

The retaining wall has a longitudinally disposed base, as 10, which may be of any desired width, length and thickness, and protruding downwardly from the underside lengthwise of the edges of the base may be two flanges, as 11 and 12. The base 10 with the flanges 11 and 12 are partially, or entirely embedded in the earth or gravel at the 60 foot or edge of an embankment, as 13, when the wall is erected, in order to properly anchor the base.

To support the required portion of the edge of the embankment I provide a wall 14 70 which may be disposed vertically, or on an incline toward the embankment. This wall is arranged to extend preferably upwardly from the top of the base 10 over the flange 11, and this wall may be of a length similar 75 to the length of the base, besides being of any desired height and thickness. The upper edge of the wall may terminate with a flange or ledge 15 which overhangs one face of the wall in opposed relation to the embankment, and this flange is a great deal narrower in width than the base 10. The wall proper may also, as occasion requires, 80 be reinforced in strength by constructing it with superimposed lengthwise protruding portions, as 16 and 17, of different thicknesses, the thickest portion being adjacent to the base 10, as shown.

Projecting at spaced intervals from the 85 face of the wall 14 as well as being disposed in opposition to the embankment are a number of web or extended members 18. These web members may be of any suitable number, besides being of any desired thicknesses and widths so as to protrude the required distances from the wall 14. The web members 90 95 18 are of heights whereby they extend vertically from the top of the base 10 to the overhanging ledge 15, and all of these members are constructed so that their free edges 100 correspondingly taper from the edge of the base 10 which is over the flange 12 to the narrow ledge 15.

Extending lengthwise of the wall 14 between the web members 18, projecting preferably 105 from the upper terminals of the protruding portions 16 and 17 of the wall are rows of longitudinally disposed ledges 19 and 20. The ledges of the row 19 are in alinement, while the ledges of the row 20 are 110

also in alinement. These rows of ledges are constructed so as to be preferably spaced equal distances between the base 10 and the top ledge 15 of the wall, and all of the ledges may be of sizes so that their free edges terminate at the free edges of the vertical web members 18. By constructing the web members of the ledges to coact in this manner, recesses or pockets, as 21, are provided on one face of the wall 14 for receiving the earth or gravel of the embankment, and serving to anchor the wall to the embankment on the underside of the free edge of each of the ledges 19 and 20 is a depending flange 21^a.

The depending flanges 21^a may be of widths so as to hang downwardly suitable distances from the ledges to form each ledge in somewhat a hook-shape for serving to effectually grip the material of the embankment. In each of the ledges 19 and 20 may be one or a number of spaced openings, as 22, 23, 24, and in each of the web members 18, between the base 10 and the ledge 19 may be an opening 25, while in each web member between the ledges 19 and 20 may also be an opening 26. The openings 22, 23, 24, 25, 26 may be of any desired shapes and sizes, though I prefer to make these openings substantially square in shape and of sufficient sizes to allow the material of the embankment to pass therethrough when the material is delivered into the pockets 21 of the wall 14. The wall will thereby be effectually anchored in the embankment by making the pockets with orificed walls as well as by providing the flanges 21^a on the ledges 19 and 20.

In the foregoing description, I have embodied the preferred form of my invention, but I do not wish to be understood as limiting myself thereto, as I am aware that modifications may be made therein without departing from the principle, or sacrificing any of the advantages of this invention, therefore I reserve to myself the right to make such changes as fairly fall within the scope thereof.

Having thus described my invention, I claim as new and desire to secure by Letters Patent:—

1. In a retaining wall, the combination with a substantially flat horizontal base having a wall member extending upwardly substantial from the forward edge thereof, of superposed spaced horizontal hook-shaped ledges and spaced vertical web members extending rearwardly from the wall member and forming with the base and wall member superposed rows of open pockets, said ledges and web members having large orifices therethrough, and said base being of greater width than the ledges.

2. In a retaining wall, the combination

with a substantially flat horizontal base having a wall member extending upwardly substantial from the forward edge thereof, of superposed spaced horizontal hook-shaped ledges and spaced vertical web members extending rearwardly from the wall member and forming with the base and wall member superposed rows of open pockets, said base being of greater width than the ledges, and said ledges being of reduced width from the lowermost one to the uppermost one. 75

3. In a retaining wall, the combination with a substantially flat horizontal base having a wall member extending upwardly substantial from the forward edge thereof, of superposed spaced horizontal hook-shaped ledges extending rearwardly from the wall member substantially parallel with and above the base, said base being of greater width than the ledges, and each ledge having large orifices therethrough. 80

4. In a retaining wall, the combination with a substantially flat horizontal base having a wall member extending upwardly substantial from the forward edge thereof, and provided with a narrow rearwardly projecting ledge at the upper edge thereof, of superposed spaced horizontal hook-shaped ledges extending rearwardly from the wall member spaced from and between the upper and lower edges of the latter, said ledges being of reduced width from the lowermost one to the uppermost one and having large orifices therethrough, and spaced vertical web members extending rearwardly from the wall member and intersecting said hook-shaped ledges. 90

5. In a retaining wall, the combination with a substantially flat horizontal base having a wall member extending upwardly substantial from the forward edge thereof, and provided with a narrow rearwardly projecting ledge at the upper edge thereof, of superposed spaced horizontal hook-shaped ledges extending rearwardly from the wall member spaced from and between the upper and lower edges of the latter, said ledges being of reduced width from the lowermost one to the uppermost one and having large orifices therethrough, and spaced vertical web members extending rearwardly from the wall member and intersecting said hook-shaped ledges, said web members tapering upwardly and forwardly substantially from the rear edge of the base to the rear edges of said hook-shaped ledges and to the narrow ledge and having large orifices therethrough. 110

This specification signed and witnessed this 24th day of May A. D. 1918.

CHARLES PAFF.
